CLAIM

The ornamental design for a wrist mounted device with non-contact type input and output function, as shown and described.

DESCRIPTION

FIG. 1 is an enlarged scale front, right side, bottom perspective view of a wrist mounted device with non-contact type data input and output function showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken line showings of the watch band and dial face are for illustrative purposes only and form no part of the claimed design.
